HANDLE FOR A BRUSH OR THE LIKE

Leonard Garth Huxtable, New York, N.Y., assignor to Kellogg Brush Manufacturing Co., Westfield, Mass., a corporation

Filed Nov. 24, 1961, Ser. No. 67,679

Term of patent 14 years

(Cl. D9—2)

FIG. 1,

FIG. 2,

FIG. 3,

FIG. 1 is a front elevational view of a handle showing my new design;

FIG. 2 is an elevational view taken from the rear of FIG. 1; and

FIG. 3 is a side elevational view thereof.

I claim:

The ornamental design for a handle for a brush or the like, as shown.
